UNITED STATES PATENT OFFICE.

JOSEPH B. LISISKE, OF SAN FRANCISCO, CALIFORNIA.

FOOT-WARMER.

1,250,330.

Specification of Letters Patent. Patented Dec. 18, 1917.

Application filed February 14, 1917. Serial No. 148,505.

To all whom it may concern:

Be it known that I, JOSEPH B. LISISKE, a citizen of United States, residing at San Francisco, in the county of San Francisco and State of California, have invented certain new and useful Improvements in Foot-Warmers; and I do hereby declare the following to be a full, clear, and exact description of the invention, such as will enable others skilled in the art to which it appertains to make and use the same.

This invention relates to improvements in foot warmers.

The object of this invention is the provision of a foot warmer especially adapted to be arranged on a standard make of radiator and so secured thereto that the heat will be confined within the foot warmer and a person may place his feet within the foot warmer in an easy and reliable manner.

A further object of this invention is the provision of a casing having one side fully open and provided with a plurality of movable blades which are adapted to be arranged between the tubes of a radiator and means connected to the casing and secured to the radiator tubes for suspending the casing thereto at any suitable height from the floor or anywhere about the length of the radiator and is provided with a door which may be lifted so as to permit access to the interior of the casing so that the feet may be placed therein and kept warm.

A still further object of this invention is the provision of a casing which can be used as a foot warmer or if desired may be used as an oven in a sick room to keep things warm and can be used at any time to warm anything that will go into the casing.

A still further object of this invention is the provision of a foot warmer of this character, which will be simple, durable and efficient, and which may be manufactured and sold at a comparatively low cost.

With these and other objects in view the invention consists of the novel combination and arrangement of parts as will be herein-after more fully described and claimed.

In the drawings:

Figure 1 is a perspective view illustrating my improved foot warmer as constructed in accordance with this invention.

Fig. 2 is a sectional view illustrating the manner in which the foot warmer is applied to a radiator,

Fig. 3 is a transverse sectional view illustrating the device applied to a radiator,

Fig. 4 is an end elevation,

Fig. 5 is a fragmentary detail perspective view of a slightly modified form of the invention,

Fig. 6 is a detail view of the modified form of the invention,

Fig. 7 is a sectional view of the modified form of the invention, and

Fig. 8 is a perspective view of a supporting plate used in connection with the modified form of this invention.

Like numerals of reference designate corresponding parts in all the figures of the drawings.

Referring more particularly to the drawings, the numeral 1 designates a casing in its entirety and this casing constitutes a foot warmer and it comprises in its construction the top wall 2, side walls 3, which side walls have formed on their lower longitudinal edges at a spaced distance apart the forwardly inclined supporting legs 4, which legs are arranged in pairs and each pair formed integrally with the lower longitudinal edges of the sides 3 and inclined forwardly as clearly shown in Fig. 1 of the drawings.

A forwardly inclined front wall 5 is formed integrally with the forward longitudinal side edge of the top wall 2 and has a depending front portion 6, which is formed integrally with the forward vertical edges of the side wall 3 and is provided on its lower longitudinally extending edge with hinges 7 to which is hingedly secured the door 8, which closes the forward front portion of the casing 1.

The rear of the casing is left fully open and the top wall 2 terminates short of the rear ends of the side walls 3 as at 9 and the top wall 2 is provided with a spaced partition wall 10, which is formed integrally with the front portion 6 as at 11, the rear end being fully open as shown in Fig. 3 of the drawings, the purpose of which will be hereinafter more fully described.

The top wall 2 is provided adjacent each end with suitable openings 12, which permit the interior of the casing 1 to be ventilated and the heat within the casing to escape therefrom.

A bottom plate 13 is removably secured to the lower edges of the side walls 3 and is

provided with an open air space 14 which forms the bottom wall 13 into sections 15, which are arranged at a spaced distance apart as shown in Fig. 3 of the drawings.

5 The bottom plate 13 comprising the sections 15 is provided with a plurality of spaced perforations 16, the purpose of which will be hereinafter more fully described.

10 A plurality of blades 17 comprising the substantially triangular shaped body portions 18, which body portions have their extreme rear edges reduced as at 19 and provided with a longitudinally extending slot 20, and the blades are removably secured 15 between the sections 15 of the bottom wall 13, as at 21 with their apexes extending rearwardly.

15 The body portions 18 are secured between the walls 2 and 10 of the casing 1, have extended from their apexes semi-circular portions 22 and the bases of these members are removably secured between the top wall 2 and partition wall 10 at a spaced distance apart.

25 The blades have their apexes arranged between the tubes or sections of the radiator and due to their movable connections with the bottom wall and top wall, they may be adjusted to fit various sized tubes of radiators so as to readily position the casing to the radiator, as clearly illustrated in the figures of the drawings.

30 The forward front longitudinal edge of the bottom wall 13 has a semi-circular curved depending flange 23 formed thereon, which flange is adapted to receive the heel portion of a shoe when the door is in an opened position, thus positioning the forward part of the foot within the casing 1 40 when the same is positioned upon the tubes of the radiator.

35 The door 8 has secured to its front face a knob 24, which facilitates the moving of the door on its hinges 7. The knob 24 may be 45 ranged under a spring 25, formed integrally with the inclined portion 5 of the top wall, thus holding the door in an opened position to permit the same to be used as the foot warmer.

40 The side walls 3 have formed integrally therewith, the laterally extending brackets 26, which brackets may be formed on the interior or exterior as clearly shown in Figs. 1 and 2 of the drawings.

55 Supporting rods 27 have one of their ends screw-threaded as at 28 and are adapted to extend through the ears 26 or brackets 35 and secured therein by the nuts 29, the free ends of the rods extend rearwardly beyond 60 the rear vertical ends of the side walls and terminate into hooks 30, which are adapted to be secured behind the tubes of the radiator as at 31, thus securely positioning the casing to the front side of a radiator and in 65 any desired position thereon.

As illustrated in Fig. 2 of the drawings, the ends of the rods 27 have the heads 32 and have arranged thereon the rectangular plate 33, which plate is slidably arranged on the rods and abuts the heads and is positioned behind the rear sides of the radiator tubes 34, thus supporting the casing 1 in position as clearly shown in Fig. 2.

70 A pair of substantially inverted V-shaped brackets 35 are secured to the bottom section 15 of the foot warming plate 13 and arranged at a spaced distance apart and have extending therethrough the rods 36, which are secured therein by nuts 37, the free ends of the rods extending rearwardly 75 beyond the ends of the plates 18 and have their ends terminating into hooks 37' or may have heads and secured to the plate 33 as illustrated in Fig. 2 of the drawings, thus 80 rigidly supporting the casing to the tubes 85 of a radiator in various positions.

The spacing of the top wall 2 by providing the partition wall 10 and the bottom being in sections 15 provides an air space, through which the heat passes and heats the 90 air forcing the same into the casing 1 formed by the sides, top and bottom walls and front walls and door so as to sufficiently heat the interior thereof and when the feet are placed within the door opening, the 95 same may be readily warmed or the door may be closed and the device used as a heating oven, as described.

95 Referring to the slightly modified form in Figs. 5, 6 and 7, there is illustrated the 100 side walls 3 which have provided on their interior, longitudinally extending sockets 38, which are provided centrally of their ends with a rectangular opening 39 in which is positioned a nut 40, the rods 27 are then 105 slidably arranged through the tubes or sockets 38 and are provided with screwthreads which receive the nut 40 thereon, and the nut is provided its faces with a plurality of 110 openings 41, which permit a key to be inserted for turning the nuts on the rods 27 to adjust the rods to support the casing 1 to a radiator, as previously described.

115 The removable connection of the plates between the walls 2 and 10 and 15 have their base portions at a spaced distance apart which permits these plates to move laterally or sidewise in various directions to fit various size tubes of the radiator, thus rendering the casing self-adjustable so that the 120 same may be secured to various size radiators having different diameters of tubes.

125 In operation, the casing 1 is positioned on the radiator, the blades are arranged to extend between the tubes, and the rods are secured on the rear side of the tubes or the plate 33 may be used, the nuts are then tightened on the rods 27 and 36 and the device is rigidly connected in position, the door 8 is lifted and its knob 24' is engaged under 130

the spring 25 and the feet are placed within the casing 1 and the heels arranged on the flange 23, thus limiting the inward movement of the feet and keeping the ball and toe 5 of the shoe or foot away from contact with the tubes of the radiator.

What is claimed is:

1. A device of the class described comprising a casing having side walls, top and bottom wall, a front wall, a door in the front wall, movable blades connected to the top and bottom walls, and means secured to the side walls for rigidly supporting the device to a radiator, as and for the purpose specified.
- 10 2. A foot warmer comprising a casing including side walls, a top wall, and front wall, a door hingedly secured to the front wall, a sectional wall, a plurality of spaced blades movably connected to the rear edge of the top and bottom walls, and means adjustably secured to the side walls for rigidly supporting the casing to a radiator, as and for the purpose specified.
- 15 20 25 3. A device of the class described comprising a casing, having its rear side fully

open, a door hingedly secured in the front wall of the casing, a plurality of spaced blades removably connected to the opened end of the casing and extending rearwardly 30 beyond the same, said blades adapted to be positioned between the tubes of the radiator, and means adjustably connected to the side walls of the casing, rigidly connecting the casing to a radiator, as and for the purpose 35 specified.

4. A device of the class described comprising a casing including side walls, a top wall, a front wall, a sectional perforated bottom wall, a plurality of blades movably connected to the rear edges of the top and bottom walls, and extending rearwardly beyond the edges of the side walls, and means adjustably connected to the side walls and bottom wall 40 for rigidly supporting the device to a radiator, as and for the purpose specified.

In testimony whereof I affix my signature in presence of two witnesses.

JOSEPH B. LISISKE.
